PROCESS FOR CLEANING PETROLEUM
REFINING EQUIPMENTWalton B. Killough, Baytown, Tex., assignor to
Standard Oil Development Company, a corpora-
tion of Delaware

Application February 12, 1941, Serial No. 378,608

1 Claim. (Cl. 196—69)

The present invention relates to improvements in the art of treating hydrocarbons, and more particularly it relates to improvements in the art of removing coke and coke-like materials from refinery equipment such as fractionating columns and the like.

Extended heat treatment of petroleum oils in refining operations results in decomposition of the hydrocarbons with the formation of polymerized products of high molecular weight. These polymerized high-molecular weight hydrocarbon compounds and salts naturally occurring in the oil or resulting from the reaction of acidic water with ammonia or other vapors that may be injected in the oil stream to prevent corrosion of metallic surfaces, usually deposit in conduits, on trays or on the walls of the chambers in which the heat treatment is taking place. It is therefore necessary in conventional practice when a particular unit such as a distillation tower becomes fouled with the above-mentioned deposits, to remove the tower from the production phase, steam the same and allow it to cool for safe entrance of workmen to remove the coke and polymerized hydrocarbons. In vessels, such as fractionation towers having trays and bubble cap plates or other equipment which effects an efficient or intimate gas or liquid contact, the cleaning of the same is a tedious, time-consuming, expensive operation which must be performed by hand.

The main object of my invention is to provide means for efficiently removing the coke-like polymerized hydrocarbons from a particular vessel such as a fractionating column in an improved manner, by the washing action of a hydrocarbon oil which is employed after the unit has been taken off the onstream operation.

It is my belief that during the refining of oils in a particular vessel, such as a fractionating tower, heavy polymers accumulate on the plates around the bell caps. These heavy hydrocarbons are subjected to heat treatment, since it is believed that the velocity of the ascending vapors is such that these polymerized hydrocarbons are carried up the tower by entrainment and eventually are held between two or more plates. As time goes on, these compounds become heavier and heavier, that is to say, they increase in molecular weight, but ordinarily remain fluid or in a suspended state until the temperature of the tower is reduced when it is removed from the onstream operation. As the temperature of the tower is reduced and the normally fluid contents are removed, the heavy polymerized hydrocarbon

or carbonaceous compounds precipitate and cement in a solid mass effectively clogging the unit. This caked mass is extremely difficult to remove from a fractionation tower, particularly since the construction of the tower is such that entry by workmen therein is difficult and the restricted area frequently hinders use of ordinary cleaning procedures. It is therefore necessary for the workmen to enter the tower after it has been steamed and cooled, to remove the coke-like products by chipping and scraping. This method of removing the caked mass is highly unsatisfactory from an economic standpoint, since valuable operating time is lost and the work constitutes a life hazard.

As previously indicated, I have devised a process for cleaning petroleum refining equipment of coke-like material and other deposits, and my invention will be best understood by reference to the accompanying drawing which shows diagrammatically apparatus which I have selected to illustrate my invention.

The drawing shows a combination of a pipe still and a fractionating column, together with other accessory equipment, and I will now describe my process as used in cleaning the fractionating tower, with the understanding that the application of the process to this particular type of equipment is purely illustrative and does not impose a limitation on my invention since heat exchangers and the like may also be cleaned by my cleaning process.

Referring in detail to the drawing, 1 represents a charging line through which a hydrocarbon oil such as a crude petroleum is introduced into the system. The charge oil is forced into coil 2 located in furnace 3, and in the furnace it is heated to distillation temperature, say a temperature of from about 525° F. to 685° F. The heated oil is withdrawn from coil 2 in furnace 3 through line 4 and, by means of pump 5 and line 6, is introduced into fractionating tower 7. Light products are removed overhead from fractionating tower 7 in line 8 and then discharged into condenser 9 where condensable hydrocarbons are liquefied and subsequently recovered by means of line 10 connecting with receiving drum 11. Liquefied hydrocarbons are recovered through line 12 while non-condensable hydrocarbons are recovered through line 13. A side-stream fraction consisting of gas oil is removed from fractionating tower 7 through line 14 may be cooled in cooler 28 and is collected in storage tank 15. Other side-stream fractions may be taken off from the tower, if desired,

through lines 26 and 27. The bottoms fraction is removed from tower 7 through line 16 and may be subsequently processed for lube oil and asphalts. In some instances the bottoms product is suitable for use as bunker fuel.

Immediately after the fires have been extinguished in furnace 3 and the oil stream has been discontinued in line 1, the oil remaining in tower 7 is pumped out through line 16 and a gas oil of 25° to 40° A. P. I. gravity is immediately charged into the top of the said tower through line 17 and pump 18 which is in communication with gas oil storage drum 15. The oil in line 17 is ordinarily provided at an initial temperature of about 100° to 150° F. as it enters the tower. Although the oil may be heated to higher temperatures it is preferable to introduce the oil at the relatively low temperatures specified above. While the flushing oil is being introduced in the top of the tower, a sufficient amount of steam is injected into the bottom of tower 7 through line 19 to maintain the temperature of the flushing oil at substantially the temperature at which it is introduced. The flushing oil, i. e., the gas oil, may be introduced into the bottom of the tower as in the conventional flow of the crude oil during the refining operation, but it is preferred to introduce it into the top of the tower above the top plate and permit it to circulate downward. The gas oil is circulated through the tower at a rate of about 100 to 20,000 gallons an hour depending on the size of the unit being cleaned. While it is preferred, for convenience, to employ a gas oil obtained during the onstream operation, I may use gas oil from any source as the flushing oil. Circulation of the oil is maintained for 1 to 24 hours to obtain effective cleaning. The oil discharging from the tower through line 16 is visually examined periodically to determine whether or not it contains suspended bodies and, when the oil no longer contains these suspended bodies, the operator knows that substantially all of the coke-like material has been removed from the tower. The oil leaving the tower through line 16 may be diverted by means of line 20 to a tank or sump 21 equipped with suitable baffles to allow settling of suspended materials flushed from the tower. After the suspended material has settled, the oil may be recirculated by means of lines 22 and 23 through the furnace 3 heated, if necessary, and pumped again to tower 7 through lines 4, pump 5, and lines 24 and 17. The precipitated polymerized matter or salts are removed from the tank or sump by any suitable means such as dredging, and this material may be mixed with material obtained through line 16 during the operating cycle to manufacture a low grade fuel such as bunker C fuel. On completion of the washing cycle as indicated by visual inspection of the washing oil, circulation of the flushing medium through tower 7 is then discontinued, and the tower is pumped free of gas oil. Steam is again injected into the tower through line 19

to remove waxy or other hydrocarbons remaining on or wetting the sides of the tower 7 or the bubble caps and trays therein. After a final wash with water which is introduced through line 25, the tower may be opened for inspection if such is deemed necessary.

It is important that the sequence of steps and the several operations described be employed since, if the oil-washing operation is not followed by steaming and water washing, it has been found that the cleaning of the tower is not as effective as when all the steps described herein are employed.

In order to further illustrate my invention, and particularly to disclose the nature of the flushing oil, the following specific example is set forth fully describing gas oils which I have found to be satisfactory in my process. It is understood, of course, that the details enumerated in the following example are purely illustrative, and other oils may be used in place of those disclosed:

Example

A virgin gas oil of the following characteristics was used in the cleaning of a fractionating tower:

Gravity	° A. P. I.	38.2
Initial boiling point	°F.	400
Final boiling point	°F.	620
Flash	°F.	184

The fractionating tower was removed from service and, before the unit was allowed to cool, it was washed with virgin gas oil at a temperature of about 110° F. for ten hours. The washing was accomplished by pumping the gas oil at a rate of 250 barrels per hour to the top of the tower and allowing it to flow downward over the trays. The oil leaving the tower was not recirculated but was drawn off and employed in another process. The tower was then steamed for safety and opened for inspection. It was found to be substantially free of coke-like deposits. The small amount of material remaining on the plates was readily removed without the usual scraping and chipping.

Many variations of my invention may be made by those familiar with this particular art without departing from the spirit of the said invention.

What I claim is:

A method for cleaning a fractionating column which comprises introducing into the column immediately after it has been removed from on-stream operation and while it is still hot, a gas-oil having a gravity in the range from about 25° A. P. I. to about 40° A. P. I., causing said gas-oil to flow downwardly through said column and removing it from the bottom thereof and introducing steam into the bottom of said column during the downward flow of gas-oil therethrough.

WALTON B. KILLOUGH.
